CONVEYOR MECHANISM FOR STRAIGHT BAR
KNITTING MACHINES
Robert M. Sanders, Reading, Pa., assignor to Textile
Machine Works, Wyomissing, Pa., a corporation of
Pennsylvania
Filed Apr. 4, 1966, Ser. No. 540,008
7 Claims. (Cl. 66—148)

This invention relates to straight bar or full-fashioned knitting machines for knitting flat selvaged fabric blanks to preformed welts and more particularly to means for conveying the preformed welts from a loading position to the knitting sections of the machine for transfer to the needles of the knitting sections.

In multisection full-fashioned knitting machines for knitting fashioned fabric blanks such as for sweaters and the like, preformed rib welts are initially topped or transferred to the needles of each knitting section and the remainder of the blank then knit thereto. Heretofore, the preformed welts were placed on transfer bars carried in carriages which were mounted for movement on a track extending along the front of the machine, around one end and along the back thereof with the carriages being connected in trains to a chain completely encircling the machine and operated by a motor. The motor is operated in one direction to move the train of carriages from a loading position on the track at the back of the machine to successively position each carriage at a loading station at the one end of the machine where the transfer bar of each carriage received a preformed welt and then along the track at the front of the machine to position the carriages at the knitting stations where the preformed welts are transferred from the transfer bars to the needles of the knitting sections. Following transfer of the welts to the needles of the respective knitting sections, the motor is operated in the reverse direction to return the trains of carriages to the back of the machine for subsequent movement through the loading station to receive other welts. While the above noted mechanism provided the motive power required to move the trains of carriages between loading and transfer positions, it was cumbersome in structure and presented a hazard to the operator when attempting to service the machine.

The principal object of the invention is to provide means in a full-fashioned knitting machine for conveying preformed welts from a loading station to a position at which the welts are transferred from the conveying means to the fabricating means of the machine which will overcome the above noted and other objections to the prior mechanism.

Another object of the invention is the provision of means in a full-fashioned knitting machine which includes means for supporting preformed fabric portions, means for conveying the supporting means between a loading station and a position at which the fabric portions are transferred from the supporting means to the fabricating means of the machine, and means extending along the front of the machine for operating the conveying means in opposite directions between the loading station and transfer position. The means also includes means for stopping and latching the conveying means in the transfer position during transfer of the fabric portions to the fabricating means and means for releasing the latching means during movement of the conveying means from the transfer position to the loading station.

With these and other objects in view, which will become apparent from the following detailed description of the illustrative embodiment of the invention shown in the accompanying drawings, the invention resides in the novel elements, features of construction and cooperation

2

of parts as hereinafter more particularly pointed out in the claims.

In the drawings:
FIG. 1 is a top plan view of a multisection full-fashioned knitting machine having transfer bar conveying mechanism according to the invention applied thereto;

FIG. 2 is a front elevational view on an enlarged scale of the operating means for the conveyor mechanism of FIG. 1;

FIG. 3 is a view on an enlarged scale of a portion of the mechanism of FIG. 2;

FIG. 4 is a view taken in the direction of the arrows 4—4 of FIG. 3, parts being shown in elevation and other parts being shown in cross section; and

FIG. 5 is a view diagrammatically illustrating the electrical control circuit for the conveyor operating mechanism.

Referring to the drawings and more particularly to FIG. 1 there is shown a portion of a multisection full-fashioned knitting machine for knitting fabric blanks such as for sweaters and the like including center frames 10, end frames 11, a back beam 12, a front beam 15 and a front bed or table 16. The beams, front bed and a center bed (not shown) are secured to the center and end frames to form the conventional framework of the machine. Each knitting section, indicated at 17, has fabricating means including a needle bar 20 provided with a row of spring bearded needles 21 which cooperate with sinkers and knockover bits to form yarn fed thereto by yarn carriers (not shown) into loops of the fabric blanks.

In the usual practice, the blanks are knitted to preformed rib welts which are initially manually placed on transfer bars 22, one for each knitting section of the machine, at a loading station, indicated diagrammatically at 25, at the front of and adjacent one end of the machine. Each transfer bar after receiving a welt is placed in a carriage 26 and the carriages which are connected to each other by links 30 to form a train are mounted for movement on a track 27. As indicated in FIG. 1, the track 27 has a straight run 31 which extends along the back of the machine, a straight run 32 extending along the front of the machine and a curved portion 35 connecting the straight runs. The train of carriages each with an empty transfer bar is initially positioned on the track 27 at a loading position with the leading carriage, indicated at 26a, at the loading station 25 to receive a welt and the trailing carriage, indicated at 26b, at the back of the machine (FIG. 1). The carriages 26 are then advanced successively to the loading station until the transfer bar of each carriage has a welt and the train of carriages is then advanced to bring each carriage to a transfer position at its respective knitting section where the transfer bars are removed from the carriages and operated, by means not shown herein and forming no part of the instant invention, to transfer the welts to the needles 21 of the knitting sections. Following transfer of the preformed welts to the needles of the knitting sections the transfer bars are returned to the carriages and the train of carriages again returned to loading position.

For moving the train of carriages 26 along the track 27 between loading and transfer positions the carriage 26a is connected at 38 to the upper run of an endless chain 36 which is trained over a driven sprocket wheel 37 and an idler sprocket wheel 40, and plates 41 and 42 carried on the framework of the machine which act to support the upper and lower runs of the chain respectively, between the sprocket wheels (FIGS. 1 and 2). The sprocket 37 is mounted on a drive shaft 45 carried in a bracket 46 mounted between the end frame 11 and adjacent center frame 10 at the left end of the machine. The shaft 45 carries a second sprocket wheel 47 which is connected by a chain 50 to a sprocket wheel 51 mount-

ed on the output shaft of a gear reduction unit 52 which is connected to and driven by a motor 55, the motor and gear reduction unit also being mounted on bracket 46. The sprocket wheel 40 is adjustably carried on a bracket mounted on the end frame 11 and adjacent center frame 10 at the right end of the machine.

The motor 55, which is of the reversible type, is connected into an electrical circuit, shown diagrammatically in FIG. 5, including main conductors of a three phase source of electrical energy indicated at 56 which are connected to buses 57, 58 and 59. The motor 55 is connected to the buses 57, 58 and 59 by leads 60 which pass through stationary contacts 61 and movable contacts 62 of a first switch or relay 65. The movable contacts 62 are carried on a core member 66 which is adapted to be operated by a coil or winding 67 when the coil is energized to move the movable contacts 62 into engagement with the stationary contacts 61. The core member 66 is biased by a spring 70 in a direction to disengage the stationary and movable contacts when the coil 67 is de-energized. The coil 67 is in a control circuit including a lead 71 which is connected to and passes through stationary contacts 72 and a movable contact 75 carried on a start button 76 of a start and stop switch 77, the stationary and movable contacts being normally biased to open position relative to each other. From stationary contacts 72 the circuit continues through stationary contacts 80 and a movable contact 81 of a normally closed stop button 82 of the switch 77 to a lead 85 which is in turn connected to a transformer 86. The transformer 86 is connected to buses 58 and 59 and is adapted to reduce the voltage from the main conductors 56 to that required in the control circuit. The circuit through the coil 67 and transformer is completed through a lead 87.

The coil 67 is also in a holding circuit for maintaining it energized including stationary contacts 90 and a movable contact 91 on the core member 66 of the relay 65 when these contacts are engaged by the movement of the core member to engage the stationary contacts 61 and movable contacts 62. The stationary contacts 90 are connected by a lead 92 through normally closed stop switches 95, 96 and 97 to the stop button 82 of the switch 77. The stop switches 95, 96 and 97 are operated by the carriages 26 as hereinafter set forth to de-energize the coil 67 to open the circuit to the motor through relay 65.

The motor 55 is also connected to buses 57, 58 and 59 by leads 100 which pass through stationary contacts 101 and movable contacts 102 of a second switch or relay 105. The movable contacts 102 are carried on a core member 106 which is operated by a coil or winding 107 when the coil is energized to move the movable contacts into engagement with the stationary contacts. The coil 107 is in a control circuit including a lead 110 which is connected to and passes through stationary contacts 111 and a movable contact 112 carried on a second start button 115 of the switch 77, the stationary and movable contacts being normally biased to open position relative to each other. From stationary contacts 111 the circuit continues through the stop button 82 of the switch 77 to the lead 85. The coil 107 is also in a holding circuit for maintaining it energized including stationary contacts 116 and a movable contact 117 on the core member 106 of the relay 105 when these contacts are engaged by the movement of the core member 106 to engage stationary contacts 101 and movable contacts 102. The stationary contacts 101 are connected by a lead 120 to the lead 92 through stop switches 95, 96 and 97 and stop button 82 of the switch 77. The relay 65 is connected to the buses 57, 58 and 59 in a manner to cause the motor to operate in a forward direction and relay 105 is connected to the buses in a manner to cause the motor to operate in a reverse direction.

The relays 65 and 105 are connected by leads 121 through stationary contacts 122 and movable 125 of a control relay 126 to a high speed winding in the motor 55. The movable contacts 125 are carried on a core mem-

ber 127 which is adapted to be operated by a coil or winding 130 when the coil is energized to move the movable contacts into engagement with the stationary contacts. The coil 130 is in a control circuit including a lead 131 which is connected to the lead 87 and a lead 132 which is connected to and passes through stationary contacts 135 and a movable contact 136 on a core member 138 of a control relay 137. From the stationary contacts 135 the circuit continues through a lead 140 and through the normally closed high speed side of high and low speed control switches 141, 142 and 143 associated with the stop switches 95, 96 and 97, respectively. From the switch 143 the circuit continues through the lead 92 and stop switches 95, 96 and 97.

The relays 65 and 105 are also connected by the leads 121 through stationary contacts 145 and movable contacts 146 of the relay 137 to a slow speed winding in the motor 55. The movable contacts 146 are carried on the core member 138 which is adapted to be operated by a coil or winding 150 when the coil is energized to move the movable contacts into engagement with the stationary contacts. The coil 150 is in a control circuit including a lead 149 connected to the lead 87 and a lead 151 which passes through stationary contacts 152 and the movable contact 136 when the coil is energized to the lead 92. The lead 151 is also connected to a lead 155 which connects the low speed side of the switches 141, 142 and 143.

In operation with the train of carriages in loading position and the carriage 26a at the loading station 25, after a welt is placed on the transfer bar 22 thereof, the start button 76 is operated to energize the coil 67 to operate the core member 66 to close the circuit from the main conductors 56 through the relay 65, to close the circuit through stop switches 95, 96 and 97 and through the high speed sides of the switches 141, 142 and 143. Closing the circuit through the high speed side of the switches 141, 142 and 143 closes the circuit through the stationary contacts 135 and movable contact 136 of relay 137 to energize the coil 130 and operate the core member 127 to close the circuit from relay 65 through relay 126 to the high speed winding of the motor 55 to operate the motor in the forward direction at high speed. Operation of the motor 55 in turn operates the chain to move the carriage 26a from the loading station 25 and to advance the next carriage in the train toward the loading station.

As the next carriage 26 approaches the loading station, a lug 156 (FIG. 2), provided on each of the carriages in the train, engages the operating button of the switch 142 to open the high speed side thereof to break the circuit through relay 137 to the coil 130 of relay 126 to permit operation of this relay to open the circuit from relay 65 to the motor and close the low speed side of the switch. Closing of the circuit through the low speed side of switch 142 energizes the circuit to the coil 150 to operate the relay 137 to close the circuit to the slow speed winding of the motor to slow the speed of the motor and chain 36. As the train of carriages continues to move the lug 156 on the second carriage engages the operating button of the stop switch 96 to open the circuit through lead 92 thereby de-energizing the coils 67 and 150 to permit operation of relays 65 and 137 to open the circuit therethrough to stop the motor as the second carriage reaches the loading station. After a welt is placed on the transfer bar of the second carriage at the loading station each of the following carriages are successively advanced to the loading station in a like manner to receive a welt.

When the transfer bar of the last or trailing carriage 26b in the train receives its welt, the starting button 76 is operated to start the motor 55 and chain 36 to move the carriages toward transfer position at the respective knitting sections for transfer of the wels to the needles of the sections. During this latter movement of the train of carriages, as the carriages approach the transfer position the lug 156 on the leading carriage 26a engages and operates the button of switch 141 to open the high speed side and close the low speed side thereof to slow the

speed of the motor and the lug 156 then engages the stop switch 95 to open the circuit and stop the motor in the same manner as switches 142 and 96.

Substantially simultaneously with the stopping of the motor 55 by the stop switch 95 the leading carriage 26a engages a stop which accurately positions the carriages at the respective knitting sections for the transfer operation and means are provided to maintain the train of carriages in the stopped position until the transfer operation is completed. For this purpose the carriage 26a carries a bracket 157 which is adapted to engage a stop screw 160 adjustably carried in a block member 161 mounted in fixed position on the framework of the machine (FIGS. 2 and 3). A latch member 162, pivotally mounted on the bracket 157, has a vertically extending surface 165 adapted for latching engagement with a surface 166 on the block member 161 when the bracket 157 is in engagement with the stop screw 160. The latch member 162 also has a camming surface 167 adapted to cooperate with a camming surface 170 on the block member 161 to raise the latch member above the block member 161 as the carriage approaches the end of its movement and the latch member is moved by gravity into latching engagement with the block member when the surfaces 165 and 166 are aligned with each other. The latch member 162 also has an arm 171 for engagement with one arm 172 of a lever 173 pivotally mounted on a stud 174 carried in a bracket 176 fixed to the framework of the machine (FIGS. 3 and 4).

A second arm 177 of the lever 173 is pivotally connected by a link 178 to a core member 179 of a solenoid 180. The solenoid 180 is connected by a lead 181 to the lead 87 and by a lead 182 through lead 118 to the stationary contacts 111 of the start button 115. The lever 173 is operated to raise the latch member 162 to disengage the block member 161 when the solenoid 180 is energized and operated as hereinafter set forth and a spring 183 connected between the link 178 and the bracket 176 turns lever 173 to the position of FIG. 4 when the solenoid is de-energized thereby permitting movement of the latch member to latching engagement with the block member when the train of carriages is in transfer position.

Following transfer of the welts on the transfer bars 22 to the needles of the respective knitting sections of the machine the start button 115 is operated to close the circuit to energize the coil 107 thereby operating the core member 106 to close the circuit from the main conductors 56 through the relay 105. Operation of the start button 115 also closes the circuit through leads 181 and 182 to energize and operate the solenoid 180 to raise the latch member 162 and release the carriage 26a, and closes the circuit through the stop switches 95, 96 and 97 and through the high speed sides of the switches 141, 142 and 143. Closing the circuit through the switches 141, 142 and 143 also closes the circuit through relay 137 to energize the coil 130 to operate the relay 126 and close the circuit from relay 105 through relay 126 to the high speed winding of the motor to operate the motor in the reverse direction thereby operating the chain 36 to move the train of carriages from transfer position toward the loading position. As the leading carriage 26a approaches the loading station 25, the lug 156 on the carriage 26b engages and operates the button of switch 143 to de-energize relay 126 and energizes the relay 137 to slow the speed of the motor 55 and chain 36 and the lug then engages the stop switch 97 to open the circuit and stop the motor and chain, in the same manner as switches 142 and 96, when the carriage 26a is at the loading station.

It will be understood that the improvements specifically shown and described, by which the above results are obtained, can be changed and modified in various ways without departing from the invention herein disclosed and hereinafter claimed.

What is claimed is:

1. In a multisection knitting machine having fabricat-

ing means for fabricating flat selvaged fabric blanks to preformed welts after transfer to said fabricating means, means for conveying said welts to a position for transfer to said fabricating means including a transfer bar for a welt for each of said knitting sections, a train of carriages on which said transfer bars are mounted, a loading station at the front of said machine adjacent one end thereof, a track on which said train of carriages are mounted for movement from a loading position, in which a leading carriage of said train is at said loading station to receive a welt and a trailing carriage of said train is at a position at the back of said machine remote from said loading station, and a transfer position in which said welts are transferred from said transfer bars to said fabricating means, means for moving said train of carriages between said loading and transfer positions during which each of said transfer bars on said carriages receives a welt at said loading station, fixed means engageable with said leading carriage for stopping said train of carriages in said transfer position, and latch means for holding said train of carriages in said transfer position during transfer of said welts from said transfer bars to said fabricating means.

2. In a machine according to claim 1 in which said moving means for said train of carriages includes an endless chain extending along the front of said machine and connected to said leading carriage in said train, and a motor for operating said chain in one direction to move said carriages past said loading station from said loading position to said transfer position and for operating said chain in a direction opposite to said one direction to move said train of carriages from said transfer position to said loading position.

3. In a machine according to claim 2 in which there is an electrical circuit for operating said motor including means for causing operation of said motor in a forward direction to move said chain in said one direction, second operating means for causing operation of said motor in a reverse direction to move said chain in said opposite direction, control means for causing operation of said motor at high and slow speeds in said forward and reverse directions, first switch means for operating said control means, said first switch means being normally conditioned to operate said control means to cause operation of said motor at said high speed, cam means on said carriages for operating said first switch means to operate said control means to change the operation of said motor from said high to said slow speeds as each of said carriages trailing said leading carriage approaches said loading station during movement of said train of carriages from said loading position to said transfer position, and second switch means for stopping said motor, said cam means on said carriages operating said second switch means to stop said motor when said carriages are at said loading station during said movement of said train of carriages from said loading to said transfer positions.

4. In a machine according to claim 3 in which said cam means on said leading carriage operates said first switch means to operate said control means to change the operation of said motor from said high to said slow speed as said train of carriages approach said transfer position, and said cam means on said leading carriage operates said second switch means to stop said motor substantially simultaneously with the engagement of said leading carriage with said fixed stop means.

5. In a machine according to claim 4 in which said electrical circuit also includes a first start switch which is operated to energize said circuit to operate said first operating means to cause operation of said motor in said forward direction.

6. A machine according to claim 5 in which said electrical circuit also includes a second starting switch which is operated to energize and operate said second operating means to cause operation of said motor in said reverse direction to move said chain and said train of carriages from said transfer position to said loading position, said

cam means on said trailing carriage operating said first switch means during movement to said loading position to operate said control means to change the operation of said motor from said high to said slow speed as said leading carriage approaches said loading station, and 5 said cam means on said trailing carriage operating said second switch means during said movement of said train of carriages to said loading position to stop said motor when said leading carriage is at said loading station.

7. A machine according to claim 6 in which said electrical circuit also includes means for operating said latch means to release said train of carriages for movement from said transfer position to said loading position when said second starting switch is operated.
